(57) **CLAIM**

The ornamental design for an electronic musical instrument body and control ring, as shown and described.

DESCRIPTION

FIG. 1 is a front perspective view of an electronic musical instrument body and control ring showing our new design; and,

FIG. 2 is a top view thereof.

The color shown on the claimed design forms no part thereof. The text shown on the claimed design forms no part thereof. The light reflections appearing within the control ring form no part of the claimed design. The bottom view (not shown) forms no part of the claimed design.

The broken lines showing portions of the electronic musical instrument body and control ring are included for the purpose of illustrating portions of the article and form no part of the claimed design.

1 Claim, 2 Drawing Sheets
